(57) **CLAIM**

We claim the ornamental design for a crossbow stock back edge, as shown and described.

DESCRIPTION

FIG. 1 is a back perspective view of a crossbow stock back edge, showing our new design.

FIG. 2 is a back view thereof;

FIG. 3 is a left side view thereof;

FIG. 4 is a right side view thereof;

FIG. 5 is a top view thereof;

FIG. 6 is a bottom view thereof; and,

FIG. 7 is a back perspective view thereof, in condition of use.

The broken line in the figure drawings represents unclaimed environment only and forms no part of the claimed design.

1 Claim, 5 Drawing Sheets
